UNITED STATES PATENT OFFICE.

JOSEPHINE BANKS, OF EAST DOUGLASS, MASSACHUSETTS.

MASSAGE-PADDLE.

1,081,923.

Specification of Letters Patent.

Patented Dec. 16, 1913.

Application filed September 26, 1911. Serial No. 651,371.

To all whom it may concern:

Be it known that I, JOSEPHINE BANKS, a citizen of the United States, residing at East Douglass, in the county of Worcester and 5 State of Massachusetts, have invented new and useful Improvements in Massage-Paddles, of which the following is a specification.

This invention relates to massage devices 10 and the object of the invention is to provide a simple, cheap and efficient device whereby the flesh may be properly massaged with a patting or slapping effect.

Further objects of this invention will appear as the following specific description is 15 read in connection with the accompanying drawing, which forms a part of this application, and in which:—

Figure 1 is a perspective view of the device partly in section. Fig. 2 is a transverse section on the line 2—2 of Fig. 1.

In the specific embodiment of the invention, as illustrated herein, the device consists in a paddle having a blade 1 which is 20 concavo-convex in cross section and is covered with an absorbent cushioning material or pad 2. Connected to and forming an extension of the blade 1, is a handle 3 and at the end of the handle, a brush 4 is mounted. This brush is provided for cleansing 25 the face or other portion prior to being treated.

To operate the device, the blade is subjected to a bath in a suitable medicated solution so as to saturate the pad 2 and the paddle used by slapping or smacking it against the portion to be treated. The flesh and muscles can be effectively worked in this manner and by the use of the device, proper circulation can be secured at any point on 35 40 the body.

Having thus fully described the invention, what I claim as new is:—

A device of the character described comprising a flat handle, a relatively wide paddle formed at the inner end of said handle, 45 said paddle consisting of an elongated intermediate portion, disposed at an inappreciable curve transversely and being countersunk with respect to said handle, and a co-extensive curvilinear upwardly extending border formed integrally upon the intermediate portion of said paddle, said upwardly extending curvilinear border having a more abrupt slant than said intermediate portion. 50 55

In testimony whereof I affix my signature in presence of two witnesses.

JOSEPHINE BANKS.
